UNITED STATES PATENT OFFICE.

THOMAS R. FERRALL, OF BOSTON, MASSACHUSETTS, ASSIGNOR TO THE BOSTON AND LOCKPORT BLOCK COMPANY, OF NEW JERSEY.

PULLEY-BLOCK.

SPECIFICATION forming part of Letters Patent No. 403,932, dated May 28, 1889.

Application filed February 26, 1889. Serial No. 301,202. (No model.)

To all whom it may concern:

Be it known that I, THOMAS R. FERRALL, a citizen of the United States, and a resident of Boston, in the county of Suffolk and State of Massachusetts, have invented new and useful Improvements in Pulley-Blocks, of which the following, taken in connection with the accompanying drawings, is a specification.

This invention relates to improvements in pulley-blocks, and particularly to that class of blocks termed "stiff swivel," and having a hook or eye journaled to one end of such block, as will hereinafter be more fully shown and described, reference being had to the accompanying drawings, wherein—

Figure 1 represents a sectional side elevation of the improved block. Fig. 2 represents a central longitudinal section thereof; and Fig. 3 represents a cross-section on the line A B, shown in Fig. 1.

Similar letters refer to similar parts wherever they occur on the different parts of the drawings.

The invention is particularly designed for double or multiple blocks, with two or more sheaves, it being constructed as follows:

a a represent the check or side pieces, and a' represents middle check, as is usual in multiple blocks.

b b and b' b' represent, respectively, the upper and lower end pieces, as usual, which parts may be of wood or metal, as may be desired, without departing from the essence of my invention.

On the upper end of the block rests, and is secured by means of bow-straps hereinafter to be described, the metal head c, in one piece, with which is made the lateral bars or saddle-pieces c' c', adapted to receive the bows or semicircular portions d' d' of the bow-straps d d, as shown. The bow-straps d d pass downward through recesses made on the inside of the respective check-pieces a a and outside of the center piece or division, a', as shown in the drawings, said bow-straps passing downward far enough to receive the sheave-spindle e, that passes through perforations made in said bow-straps, the check-pieces, and center piece. On said spindle or bolt e are loosely journaled the sheaves f f, in any ordinary or suitable manner, with or without

anti-friction rollers, according to the quality or construction of said sheaves, as may be desired. The end pieces, b b, b' b', are riveted or otherwise firmly secured to and between the center and check pieces, as usual.

To the metal head c is journaled the shank g' of the hook or eye g, as shown in Fig. 2, said shank g' being provided with a rivet-head, g'', on the under side of the head c, as shown in said Fig. 2, so as to permit the said shank g' to turn around its axis in the vertical perforation in said head c. In a vertical recess in the center piece, a', and between the inner portions of the bow-straps d d, is located the metal becket-strap h, that projects upward far enough to receive the sheave-spindle e, as shown, said becket-strap having an eye, h', in its lower end adapted to receive the becket i, as shown in Figs. 1 and 2.

By this arrangement and construction I am able to produce a double or multiple block with a stiff swivel hook or eye in a very strong, durable, and simple manner, composed of very few parts, easily made, and easily put together. By the construction as shown and described the strain on the block is conveyed from the hook or eye g directly to the spindle e by the medium of the metal head c c' c' and the wrought-metal bow-straps d d' d d' without causing any strain whatever on the body of the block. In a like manner the strain on the becket i is conveyed directly to said spindle e by the medium of the metal becket-strap h, as above described and shown in the drawings.

I have represented in the drawings a block with two sheaves only; but the block may be provided with an increase of sheaves and corresponding bow-straps and division or center pieces without departing from the essence of my invention.

What I wish to secure by Letters Patent and claim is—

1. In a double or multiple block, the head c and its lateral bars or saddle-pieces c' c', and hook or eye g g', journaled and loosely riveted to said head, combined with the bow-straps d d', the block-body, and the spindle e, with its sheaves f f, substantially as and for the purpose set forth.

2. In a double or multiple block, the head

c, and hook or eye *g g'*, loosely riveted to said head, the block-body having the bow-straps *d d'* suspended from the lateral bars or saddle-pieces *c' c'* of the head *c*, the spindle *e*, passing through the block-body, its sheaves, and bow-straps, and the becket-strap *h*, suspended from the sheave-spindle and provided with the becket *i*, substantially as and for the purpose set forth.

In testimony whereof I have signed my name to this specification, in the presence of two subscribing witnesses, on this 1st day of February, A. D., 1889.

THOMAS R. FERRALL.

Witnesses:

ALBAN ANDRÉN,
SELMA R. SCHELIN.
